UNITED STATES PATENT OFFICE.

GÉZA L. TERNA, OF DETROIT, MICHIGAN.

DRAFTING AND LAY-OUT INSTRUMENT.

Application filed December 29, 1923. Serial No. 683,322.

This invention relates to improvements in compass-type instruments and more particularly to an improved instrument by which tracery, ovals, curves, circles, ellipses, spirals 5 and other conchoidal, crescentic or devious delineations may be readily formed.

The primary object of the present invention is to provide a lay-out or drawing instrument, by the manual manipulation of 10 which, curves of various characters may be automatically generated, corresponding to the adjustment of a controlling mechanism, and absolute ideal curves delineated.

More specifically, the invention has for an 15 object to provide a curve-drawing instrument employing a marking element adapted to be moved about a centering element in the formation of a curve with guiding means adapted to automatically assume positions 20 controlling the movement of the marking element in a path varying in distance from the centering element.

Another object of this invention is to provide controlling means for the guiding 25 means whereby the proportions and the character of the curve generated may be quickly and accurately altered.

A still further object of the invention is to provide holding means preventing rotation 30 of the controlling means with the marking element under the manual manipulation of the latter to outline a curve.

Other objects of this invention will be 35 apparent from the following description and claims.

In the drawings,

Figure 1 is a side elevation of the instrument;

Fig. 2 is an edge view of the upper portion 40 of the instrument, partly in vertical section and illustrating different positions of the guiding elements;

Fig. 3 is a horizontal sectional view taken on the line III—III of Fig. 2;

Fig. 4 is an enlarged side elevation of a portion of the instrument, partly in section;

Fig. 5 is a vertical cross sectional view of the same showing the guiding element in contact with a control element;

Fig. 6 is a perspective view of the instrument illustrating the manner of manipulating the same in the generation of an ellipse or oval;

Fig. 7 is an edge view of the upper portion

of the instrument showing different positions of the controlling and guiding elements;

Fig. 8 is a side elevation of a portion of an instrument including another form of guiding element;

Fig. 9 is a plan of the same, and

Figs. 10, 11, 12, 13 and 14 are views showing different configurations that may be delineated by the instrument.

In the drawing there is shown an instrument somewhat in the form of a compass comprising a pair of legs 1 and 2, the leg 1 having a central or pivot pin 3 and constituting a centering element, while the leg 2 has a marking instrumentality 4 and constitutes a marking element which may be shifted relative to the centering element. The upper ends of the legs 1 and 2 terminate in hollow heads 5 and said heads are pivotally connected by a pivot pin 6 on which is mounted a coiled spring 7 having its ends bearing against the heads 5 so that the expansive force of said springs will tend to separate said legs.

The pivot pin 6 supports the side ears 8 of a yoke 9 and the side ears are provided with longitudinal slots 10 for a transverse equalizing pin 11, which may be in the form of screws with anti-frictional sleeves or rollers thereon, said pin extending through angularly disposed slots 12 in the heads 5 of the legs 1 and 2. The slot 12 of one leg is disposed at a right angle to the slot 12 of the opposite leg, as shown by dotted lines in Fig. 4, and with the legs urged apart by the coiled spring 7, the extent of movement of one leg is necessarily equal to that of the other leg, consequently the yoke 9 always remains in a line bisecting the angle between the spread legs. This is one form of equalizing device 85 that may be advantageously used without any great change in the usual heads of a compass.

On the yoke 9 is a spindle 13 having a threaded upper end 14 and a finger piece 15 100 and in some instances a crank 16 or the like (see Fig. 2). Loose on the smooth portion of the spindle 13 is a sleeve 17 having its lower end provided with a peripheral flange or seat 18 and loose on said flange or seat is 105 a support 19 having diametrically opposed arms 20, one of which has a wing or finger piece 21. The outer ends of the arms 20 are

provided with universal joints or connections 22 for a guiding device or pattern-disk 23 which is in the form of a flat annulus that may be tilted on an axis at a right angle to the axis of the spindle 13, so that in plan view its circular outline may be evolved into that of an oval or ellipse, as will hereinafter appear. The lower face of the guiding element 23 constitutes a track and the upper face of said guiding element affords a stop surface adapted to be engaged by one or two diametrically opposed adjustable control elements 24 carried by the support 19 in a plane at a right angle to the equatorial axis about which the guiding element turns. The controlling elements 24 are preferably in the form of fingers which may be adjusted and set relative to the support 19 and different positions of these fingers have been shown in Figs. 2 and 7.

The marking element or leg 2, adjacent its head 5, is provided with longitudinal intersecting slots 25 and 26. Slidable in the slot 25 and adapted to be fixed relative to the leg 2 is a set screw 27 or other clamping element adapted for holding the forked or bifurcated end 28 of a segment shaped arm 29 which extends through the slot 26 and may be shifted therein and fixed relative to the leg 2 by the set screw 27. On the upper end of the arm 29 is an anti-frictional bearing 30 which engages the lower track face of the guiding element or pattern-disk 23. Outward movement of the leg 2 relative to the leg 1 is limited by the arm 29 engaging the guiding element 23 and tilting of this guiding element is defined by the position of one or both of the controlling elements 24.

The upper end of the threaded sleeve 17 is split or bifurcated to provide a plurality of clutch jaws 31 which are sprung outwardly and are adapted to be shifted inwardly into screwthreaded engagement with the threaded portion of a spindle 13, so that when said spindle is rotated by the finger piece 15 or preferably the crank 16, the sleeve 17 will be fed on the spindle and raised or lowered according to the direction in which the spindle is rotated. This is accomplished by providing the sleeve 17 with a nut 32 that can be secured on to the jaws 31 or backed off of said jaws, the nut when in engagement with said jaws establishing a driving relation between the spindle and sleeve, where-by if the finger piece 21 is loosely held in one hand, to prevent rotation of the support 19, and the spindle 13 revolved by the other hand, the sleeve 17 will be shifted longitudinally of the spindle and may assume the position shown in Fig. 5.

Before considering another form of guiding element as shown in Figs. 8 and 9, the manner of using the instrument will be considered.

Assuming that the ellipse or oval is to be

drawn or points laid out by which different curves may be joined to produce the outline of the ellipse or oval shown in Fig. 6, the instrument is placed in position for the minor axis, (one-half of such axis being represented by the spread or distance between the lower ends of the centering and marking legs 1 and 2.) With the instrument in such position the arm 29 is adjusted until it engages the guiding element 23 and then the arm 29 is fixed relative to the marking leg 2 by the set screw 27. This adjustment is performed with the legs 1 and 2 in approximately the vertical plane of the arms 20 of the support 19, so that the arm 29 will be substantially under one of the universal joints of the guiding element or pattern-disk. Such adjustment defines the spread of the marking leg 2 relative to the centering leg 1 as far as the minor axis of the ellipse is concerned, and to prepare the instrument for a major axis, with the centering leg still in position, the marking leg 2 is swung to one of the extreme points of the major axis. This of course means a greater spread of the marking leg 2. Then the controlling element or finger 24 above the raised edge of the guiding element is brought downwardly on to the upper face of said element and set. The instrument is then swung so that the other controlling element or finger 24 may be set relative to the raised edge of the guiding element or pattern-disk 23, thus positioning the two controlling elements or fingers to define or limit the spread of the marking leg 2 as far as the major axis is concerned.

The instrument having been set for these two axes, the finger piece 21 is now held in one hand, as best shown in Fig. 6, to maintain the support 19 stationary, but not interfere with tilting of the guiding element on its axis. The other hand is then used to twirl or turn the finger piece 15, and remembering that the spring 7 is tending to constantly spread the free ends of the centering and marking legs, it is obvious that the spread of said legs will be in ratio with the movements of the guiding elements or pattern-disk 23 relative to its support. Assuming that the instrument is to be turned in a clockwise direction, with reference to Fig. 6, the marking leg 2 will gradually increase its radius from the centering leg and in so doing tilt the guiding element or pattern-disk until one side of the guiding element impinges against one of the said controlling fingers 24. As the arm 29 passes under the controlling element the extreme curve at one end of the major axis is described by the instrument and from such point on the radius gradually decreases for the minor axis, until the instrument is in an opposite position from that shown in Fig. 6. From then on the radius increases for the marking element causing the guiding element to be

tilted in a reverse direction until it impinges against the other controlling element or finger 24, which defines another extreme of the major axis. The tilting of the guiding element or pattern-disk 23, for two extreme major axis positions has been brought out in Fig. 2.

It should now be apparent that if the controlling elements or fingers 24 define major axis extremities for the marking element 2, that either one of these controlling elements or fingers may be adjusted to limit the tilting of the guiding element, and in consequence of such adjustments the substantially heart shaped configurations shown in Figs. 10 and 14 may be produced.

The instrument may also be used for generating a spiral configuration, as shown in Fig. 12, or an elongated spiral as shown in Fig. 13. To do this the marking leg limits for the minor and major axes of the inner or small spiral convolution are set, just as though a single ellipse was to be produced, and then the nut 32 is adjusted to establish a driving relation between the spindle 13 and the sleeve 19. Lightly holding the finger piece 21, to prevent rotation of the support 19 and yet not interfere with vertical movement of said support, the finger piece 15 or the crank 16 is turned and the sleeve 17 fed upwardly on the spindle 13. This of course causes the guiding element or pattern-disk 23 to be gradually and uniformly raised as the marking element 2 is swung about the centering element 1. Since the guiding element is raised there will be a gradual spread of the marking element relative to the centering element, and since the controlling element or fingers 24 are raised by the support 19, it is obvious that these controlling elements will cooperate with the arms 20, the guiding element 23 and the arm 29, in defining the minor and major axes for each convolution or configuration or rotation of the instrument. Bearing in mind that the controlling elements or fingers 24 are independently adjustable, it is possible to produce a wide range of spiral configurations from that shown in Fig. 12 to extremes beyond that shown in Fig. 13.

A further development of my invention is the substitution of another form of guiding element or pattern-disk for that just described, and by reference to Figs. 8 and 9, it will be noted that the guiding element or pattern-disk 33 has an undulating configuration and its upper and lower faces may present angularly related surfaces, which in some instances may be more or less tortuous or irregular for the production of various configurations. With such obtuse angular faces on the guiding element or pattern-disk 33 it is possible to produce square or regular configurations, one of which is shown in Fig. 11, and as illustrat-

ing a modified form of connection between the arms 20 and the guiding element or pattern-disk, I show the guiding element 33 as having depending apertured ears 34 provided with trunnions 35 for apertured extremities or lugs 36 of the support arms 20. It is an extremely easy matter to remove one support and its guiding element and substitute another therefor.

It is thought that the manner of using the instrument will be apparent without further description, and while in the drawings there are illustrated the preferred embodiment of my invention, it is to be understood that the structural elements are susceptible to such changes in size, shape and manner of assembling, as fall within the scope of the appended claims.

What I claim is:

1. In a curve-drawing instrument, the combination of a centering-element adapted to have its lower end serve as a pivot, a marking-element pivotally connected to said centering-element so that the lower end of said marking-element may be swung relative to the pivot end of said centering-element in the formation of a curve, a pattern-disk supported from above the pivot of said centering and marking elements for movement by said marking-element engaging the lower face of said pattern-disk during a curve-drawing operation, and means adapted to limit the movement of said pattern-disk and thus determine the movement of the marking-element in a path varying in distance from the centering-element in the formation of a curve of predetermined proportions.

2. In a compass-type curve drawing instrument, the combination with a pair of pivotally connected legs having free ends limited in relative movement toward and from each other, of means supported by said legs and adapted to be engaged and tilted by one of said legs during a curve drawing operation for automatically varying the extent of spread of the legs throughout the formation of a curve of predetermined proportions.

3. In a compass-type curve-drawing instrument, the combination with a pair of legs having adjacent ends limited in relative movement to from and toward each other, of means supported by said legs and including a pattern-disk, adapted to be engaged and tilted by one of said legs during a curve-drawing operation for automatically varying the extent of spread of the adjacent ends of the legs in the formation of a curve.

4. A curve-drawing instrument as called for in claim 1, and means adapted for bodily shifting said pattern-disk and the last mentioned means to increase or decrease the path to be traversed by the marking-element.

5. In a compass-type curve-drawing instrument, the combination with a pair of

legs having free ends relatively movable to each other, of a tiltable pattern-disk adapted to be tilted by one of said legs, means on said legs tiltably supporting said pattern-disk, means for limiting the movement of the pattern-disk relative to its leg supporting means, and yielding means for maintaining the spread of the free ends of the legs so that one of said legs will be operatively held relative to said pattern-disk for tilting said pattern-disk.

6. In a compass-type curve-drawing instrument, the combination with pivotally connected legs having free ends relatively moveable to each other, a pattern-disk, a support for pivotally mounting said pattern-disk the pivotal axis being maintained substantially in the horizontal plane of the pivot of the legs, a projection on one of said legs adapted to contact with said pattern-disk, and means for limiting the movement of the pattern-disk relative to its support in accordance with the nature of the curve.

7. In a compass-type curve-drawing instrument, in combination, a pair of pivotally connected legs, a pattern-disk supported for tilting movement thereby, a projection upon one of said legs, means for yieldingly maintaining the same in contact with said pattern-disk, opposed guide-elements in a plane at a right angle to the tilting axis of said pattern-disk for controlling the movements of said pattern-disk, said guide elements being adjustable in a vertical plane to vary the nature of the curve produced.

8. In a compass-type curve drawing instrument comprising a pair of pivotally connected legs of which one leg is turned about the other in the formation of a curve, in combination, a pattern-disk supported from said legs for movement about an axis, a projection on one of said legs adapted to contact with said pattern-disk, controlling means in a plane at a right angle to the axis of said pattern-disk adapted to be engaged by said pattern-disk for limiting the tilting movement of the pattern-disk in accordance with the nature of the curve, and means for maintaining said controlling means stationary relatively to the turning movement of one of said legs about the other.

9. In a curve-drawing instrument, the combination of a centering-element adapted to have its lower end serve as a pivot, a marking-element supported from said centering-element so that the lower end of said marking-element may be swung relative to the pivot end of said centering-element in the formation of an oval, tiltable means actuated by said marking-element for guiding the movement of the marking-element in a path from the extremities of a minor axis through the extremities of a major axis in the formation of the oval, and means engageable by the first mentioned means for

defining the proportions of the oval to be produced.

10. In a curve-drawing instrument, the combination of a centering-element adapted to have its lower end serve as a pivot, a marking-element supported from said centering-element so that the lower end of said marking-element may be swung relative to the pivot end of said centering-element in the formation of a curve, and a guiding-element for said marking-element adapted to freely move under the influence of said marking-element to assume positions defining an oblique projection of a circle upon the drawing surface, and means engageable by said guiding-element to define the degree of oblique projection.

11. In a curve-drawing instrument, in combination, a centering-element, a marking-element pivotally connected to said centering element and movable about the centering-element in the formation of a curve, a guiding element for said marking-element in approximately the horizontal plane of the pivotal connection of said centering and marking-elements adapted to automatically assume positions defining an oblique projection of a circle upon the drawing surface whereby a true ellipse may be formed by the movement of said marking element, and means for determining the angle of the oblique-projection path of movement for correspondingly varying the proportions of the ellipse.

12. In a curve-drawing instrument, the combination of a centering-element adapted to have its lower end serve as a pivot, a marking-element supported from said centering-element so that the lower end of said marking-element may be swung relative to the pivot end of said centering-element in the formation of a curve and a spindle sustained by said elements, of a support on said spindle, a guiding-element held by said support for tilting movement, a projection upon the marking-element yieldingly maintained in contact with the lower face of the guiding-element, and means adapted for engagement with the upper face of the guiding element for automatically controlling the positions of the guiding-element during the turning of the marking-element about the centering-element in the formation of a curve.

13. In a curve-drawing instrument, the combination with a centering-element, a marking-element pivotally connected with and movable about the centering element in the formation of a curve, and a spindle sustained by said elements, of a guiding-element, a sleeve sustained by said spindle and tiltably supporting said guiding element, a plurality of adjustable controlling fingers projecting from said sleeve, and means carried by the marking-element for causing

said guiding-element to tilt to engage said fingers to thereby determine the path of movement of said marking-element in the formation of a curve.

- 5 14. An instrument of the type described comprising a marking leg, a centering leg, connecting means for said legs, means for spreading said marking leg relative to said centering leg, tilttable guiding means engageable by a portion of said marking leg and regulating the spread of said legs, and yieldable controlling means for said guiding means operable by said guiding means during the drawing operation.
- 10 15. In a drawing instrument, a marking leg, a centering leg having upper pivotally connected ends, a spindle adapted to be twirled to move the marking-leg about the centering leg, means at the pivot of said legs tending to separate said legs, means supported from said spindle and having a guiding surface surrounding said centering leg, and an adjustable arm carried by said marking leg and engaging the guiding surface of said means for controlling the degree of leg separation, said guiding means being
- 15 tilttable by said arm and movable bodily in a vertical direction relative to said spindle.
16. A drawing instrument comprising a spindle, pivoted legs carried by said spindle, means constantly tending to spread said legs apart, and guiding means supported from said spindle and surrounding the pivot of said legs, for holding one leg so that it may be swung about the other leg to generate a circle, said guiding means being tilttable by one of said legs and manually movable in a direction bi-secting the angle of leg spread so that a spiral may be generated.
- 20 17. A drawing instrument comprising a spindle, pivoted spring pressed legs carried by said spindle and constantly tending to spread, and an annulus supported from said spindle about the pivot of said legs and having its center constantly in a line bi-secting the angle of leg spread, said annulus being engaged by one of said legs to limit the spreading action of said legs, said annulus being adjustable relative to said spindle for the generation of a spiral.
- 25 In testimony whereof I affix my signature.

GÉZA L. TERNA.
